DETACHABLE TOOLHOLDER

Clifford H. Snyder, Dormont, Pa., and Douglas A. Turner, Salem, Ohio, assignors, by mesne assignments, to The Colmol Company, New Lexington, Ohio, a corporation of Ohio

Application September 8, 1949, Serial No. 114,553

1 Claim. (Cl. 279—79)

This invention relates generally to tool holders, and more particularly to holders for detachably retaining bits such as mining machine bits.

The principal object of this invention is the provision of a tool holder that is adapted for quickly changing the tool therein without the use of special tools for such purpose. This invention also contemplates a strong support for transmitting heavy loads subjected to the tool without stressing or otherwise interfering with the tool retaining means.

This invention is particularly advantageous for detachably supporting coal chipping bits on cutting bars, or rotary coal chipping heads wherein the bits are radially spaced, progressively receding axially and are disposed angularly to the plane of the coal face. The simultaneous forward feed and rotation of the coal chipping head moves the bits along spaced concentric helices. The traveling bits thus constantly cross the horizontal and vertical cleavage planes of the coal causing it to chip out usually ahead of the advancing bits. The varying pressure load produced by the character of the coal and other substances encountered in digging is transmitted from the teeth through a shoulder and stem to a socket fixed on the chipping head and thence through the head and rotary shaft on which it is supported. This stem is disposed normally to the shoulder from which the teeth extend and can be constructed materially stronger than the teeth. The juncture of the stem and shoulder and the tips of the teeth may be the weakest links in the structure, but are designed to be the first break. The socket has yet to break in service even though some play is desirable between the stem of the bit and the socket in which it fits.

The means of locking the bits in the socket represent an important object of this invention. This lock is obtained by a spring arm having an inturned tongue that passes through a window in the socket or the bit and extends into a pocket in the bit. This pocket being preferably larger than the tongue and spaced from the bit shoulder so that it will function only as a retaining means. This spring locking arm is mounted to be shielded from contact with the coal and has been found to be undisturbed even when the teeth or stem of the bit is broken. However, the spring locking arm may be readily pried up to permit withdrawal of the bit by a knife, screw driver, or other similar pointed instrument at hand. Upon prying up the tongue from the pocket of the bit, the latter may be readily withdrawn from the socket and replaced.

Other objects and advantages appear hereinafter in the following description and claim.

The accompanying drawings show, for the purpose of exemplification without limiting the invention or claim thereto, certain practical embodiments of this invention wherein:

Fig. 1 is a plan view of the socket comprising this invention having a mining machine bit secured therein;

Fig. 2 is a sectional view taken on the line 2—2 of Fig. 1;

Fig. 3 is a transverse sectional view taken on the line 3—3 of Fig. 1;

Fig. 4 is a transverse sectional view taken on the line 4—4 of Fig. 2;

Fig. 5 is a view partially in section showing another type of socket and locking means;

Fig. 6 is a side elevation of the structure shown in Fig. 5;

2

Fig. 7 is a transverse sectional view taken on the line 7—7 of Fig. 5;

Fig. 8 is a transverse sectional view taken on the line 8—8 of Fig. 6;

Fig. 9 is a top plan view of a third type of detachable tool holder;

Fig. 10 is a sectional view taken on the line 10—10 of Fig. 9;

Fig. 11 is a transverse sectional view taken on the line 11—11 of Fig. 9;

Fig. 12 is a transverse sectional view taken on the line 12—12 of Fig. 10; and

Fig. 13 is a sectional view of a modified socket structure similar to that shown in Fig. 10.

Referring to Figs. 1 to 4, the socket member 1 comprises a body having a rearward extension 2 forming the shoulder 3 that may be employed to attach the socket to a rotary chipping head or other device with the use of a cap nut or other similar device. The shoulder 3 may be employed to clamp the socket to the body or the latter may be welded or otherwise attached to the member on which the socket is to be mounted. The socket 1 is provided with a bore 4 for the purpose of receiving the stem 5 of the bit 6. The bit body is provided with a transverse shoulder 7 arranged to engage the annular surface 8 that surrounds the bore 4 of the socket. Extending from the body of the bit 1 are a plurality of teeth 10 and 11. The tooth 10 is longer than the tooth 11, extending farther from the socket than the latter. Both teeth are formed integral with the bit and extend in opposite directions forming the V-shaped device in the center thereof as indicated at 12.

Such a bit could be employed as a center tool or pilot bit of a rotary chipping head. The bit, as shown in Figs. 1 and 2, was designed for the purpose of acting as a pilot bit rotating in a counterclockwise direction when viewed from below in Figs. 1 and 2. The rear side of the teeth are backed off as indicated at 13 providing a negative rake. The bore 4 may be square or rectangular in cross section and so in the mating stem 5 of the bit 6. This nonround bore transmits the rotary power to the complementary shaped bit stem.

The bit is provided with a pocket 14 on one side of the stem or shank thereof, the stem being preferably of square or rectangular cross section as indicated in Figs. 3 and 4. The pocket 14 is arranged to open into the window 15 of the socket 1 when the shoulder 7 of the bit engages against the annular surface 8 of the socket. Extending from the window or lateral opening 15 to the rear of the socket is an axially disposed recess 16 which is of sufficient depth to receive the flexible arm 17 made of spring material, making its outer surface flush with the socket surface. The flexible arm 17 is secured to the socket by means of the screws 18 and 19 which are fastened in threaded openings in the socket 1. The outer end of the flexible arm 17 is provided with an inwardly depending tongue 20 arranged to pass through the opening or window 15 into the pocket 14 in the side of the shank or stem 5 of the bit. A transverse pry slot 21 is provided across the face of the socket 1 and is lower than the recess 16 for the purpose of permitting the insertion of a knife, screw driver or other type of sharpened implement for the purpose of prying up the flexible arm 17 to withdraw the tongue 20 from the pocket 14, and thereby release the bit from the bore 4 of the socket.

The single toothed bit as shown in Figs. 5 to 8, wherein the bit 22 is provided with the shoulder 23 that engages against the annular shoulder 24 of the socket 25, shows the socket 25 welded to one face of the arm 26. The socket 25 has a bore 27 extending therethrough for the purpose of receiving the stem 28 of the bit 22. The stem 28 extends from the shoulder 23 to the end of the bore of the socket as illustrated in Fig. 5. The socket 25 is provided with two oppositely disposed windows 30 and 31 which are in alignment with each other. The recess 32, to receive the spring locking arm, extends from the window 30 around the back of the socket to the window 31 for receiving the U-shaped flexible arm or spring member 33 that has inwardly projecting tongues 34 and 35, that engage in corresponding pockets on

opposite sides of the stem 28. Each side of the socket 25 is provided with the transverse slots 36 and 37 to receive a sharpened implement for the purpose of spreading the spring member 33 to withdraw the tongues 34 and 35 from the pockets in the sides of the stem of the bit, thereby permitting the bit to be withdrawn from the socket.

In the structure shown in Figs. 9 to 12, the socket member 40 is secured to the chipping head arm 41 and the top side of the socket is provided with the spring arm recess 42 that extends along the top and down the back of the socket as indicated in Fig. 10. In this showing the bit 43 is provided with the shoulder 44 and has two projecting teeth 45 and 46. The bit 43 is provided with the rearwardly extending stem 47 that is square for the purpose of fitting the square bore 48 of the socket 40. The stem 47 is provided with a pocket 50 that is in alignment with the window or opening 51 through one of the socket walls. This window is likewise at the end of the recess 42. The flexible arm or spring 52, having the inwardly extending tongue 53, lies in the recess 42 and its tongue is arranged to engage through the window 51 into the pocket 50 of the stem of the bit. This flexible arm or spring 52 extends rearwardly and downwardly along the recess 42 and back along the top surface of the chipping head 41 and is secured thereto by the screws 54. A transverse slot 55 is cut in the top surface of the socket 40 for the purpose of permitting the insertion of a pointed implement under the spring arm 52 to withdraw the tongue 53 from the pocket 50 and permit the bit to be withdrawn from the bore 48 of the socket 40. As in Fig. 5, the bore 48 extends through the socket 40 and the rear end of the stem 47 is substantially covered by the spring arm 52.

As in each of the structures previously described, the prying slot that extends across the face of the socket is cut below the recess to permit the sharpened implement to be inserted underneath the spring arm.

By thus properly disposing the teeth on the bit with reference to the socket in which it is to be inserted, the spring arm, which detachably holds the bit or tool in the socket, is protected from direct contact of the coal when the tool is in use. However, any pointed or sharpened implement may be employed to flex the spring arm and thereby release the bit from the socket. In each of the structures disclosed, the stem is of rectangular cross section and is inserted in a complementary bore in the socket. Although there is no clearance shown between the stem and the bore of the socket, such clearance is preferable to permit ready insertion or withdrawal of the bit into the socket.

The body or head member 41, as shown in Fig. 13, is provided with the socket 56 which has a bore 57 extending therethrough for receiving the shank or stem 58 of the bit 60. The bit 60 is similar in design to that shown in Figs. 9 and 10, with the exception that the teeth 61 extend forwardly of the socket. The socket 56 is provided with the spring arm recess 62 which extends laterally along the outer face and down the back thereof as shown in the drawing. The body of the bit is provided with a lateral pocket member 63 providing a shoulder 64 for the reception of the inwardly projecting tongue 65 of the spring arm 66 which is secured to the body member 41 by means of the screws 54. In this instance the socket is not provided with a window nor

with a transverse clearance slot, but these parts are replaced by the pocket 63 and the shoulder 64 within the body of the bit 60 and sufficient clearance is allowed below the tip of the tongue to permit the insertion of the pointed implement for the purpose of prying the tongue and flexing the spring 66 so as to permit ready removal of the bit 60 from the socket 56.

Thus, in the structure as shown in Fig. 13, the pocket in the shank of the tool has been replaced by the pocket 63 in the body of the bit which also functions as a transverse clearance slot for the purpose of prying the flexible arm to release the bit from the socket.

While, for clarity of explanation, certain preferred embodiments of this invention have been shown and described, it is to be understood that this invention is capable of many modifications, and changes in the construction and arrangement may be made therein and certain parts may be employed without conjoint use of other parts and without departing from the spirit and scope of this invention.

We claim:

A holder for detachable mining machine bits comprising a square tubular socket having at least three outer flat faces and mounted on the arm of a mining machine cutting head, a square bore in said socket, at least three lateral force transmitting surfaces around the mouth of said bore and corresponding to said outer flat surfaces, a bit having a square body, a square shank extending from the lower side of said body and fitting in but shorter than said square bore to retain said bit from turning and to transmit some of the digging forces of the bit to the arm of the cutting head, a pocket in the rear face of said shank, a shoulder on at least three sides of said body at its juncture with said shank, said shoulders mating with said lateral force transmitting surfaces on said socket to transmit other of the digging forces of the bit to the arm of the cutting head, tooth means projecting from the upper side of said bit body above the plane of said shoulders, a longitudinal recess extending the full length of the intermediate of said outer flat surfaces of said socket, a flat bit retaining spring fitting in said recess and having one end secured relative to said socket, an in-turned tongue on the other end of said spring extending into said bore and into said shank pocket when said shoulders engage said lateral force transmitting surfaces to prevent accidental displacement of said bit from said socket, and a pry slot in said outer flat surface extending across and deeper than said recess and inwardly of said tongue to receive a wedge under said spring to pry said tongue from said pocket to replace said bit.
